TUBULAR KIT

Murray Dulberg, New York, N. Y.

Original application September 24, 1948, Serial No. 50,999, now Patent No. 2,695,028, dated November 23, 1954. Divided and this application August 2, 1954, Serial No. 447,287

4 Claims. (Cl. 132—79)

This invention relates to kits containing articles related in use for a special purpose and more particularly to a tubular kit capacitated to contain or carry cosmetic materials and applicators. This application is a division of my co-pending application Serial No. 50,999, filed September 24, 1948, now Patent No. 2,695,028, issued Nov. 23, 1954.

It is the general object of the present invention to provide a convenient and compact unitary kit, whose outward appearance is that of a fountain-pen, for housing a plurality of cosmetic or other articles related in use, such articles being retained within the kit in such a manner as to be protectively carried therewithin when not in use, at the same time, being readily accessible and exposable for use when and as required.

A further object of the invention is the provision of an outfit of the character indicated, comprising a plurality of separate elements or articles related in use for a special purpose, designed and constructed in such a manner as to readily facilitate selective disposition of a particular element or elements in operative position for application.

A still further object of the present invention is to provide a tubular kit having an elongated outer casing serving not only as a means for holding separate articles in axial alignment but, also, functioning as a handle in the application of each of the separate articles.

The foregoing objects as well as additional objects and advantages of the invention will be readily apparent in the course of the following detailed description taken in connection with the accompanying drawings which illustrate, by way of example, a preferred embodiment of the invention, and wherein—

Fig. 1 is an elevational view of a device embodying the features of the invention, the device being in assembled condition with the end caps attached;

Fig. 2 is a view similar to Fig. 1, with the end caps shown removed and spaced from the outer casing member and the protruding end portions of unitary sections;

Fig. 3 is a view similar to Fig. 1 but, with the outer casing being indicated by dashes, and showing the end portions of the unitary sections normally frictionally and telescopically retained within opposite ends of the outer casing;

Fig. 4 is a view similar to Fig. 1 but, with the outer casing being indicated by dashes, and the end caps of the separate sections being also indicated by dashes, and showing the opposed threaded portions of the connector member, walled handle and end cap.

Referring now to the drawings in detail, the device comprises a preferably cylindrical outer casing 10 for housing articles. It will be understood that the articles retained within outer casing 10 are not to be restricted to the cosmetic articles illustrated in the drawings, but may be in the form of other suitable articles assembled for a common purpose.

In the illustrated preferred embodiment of the present invention, outer casing 10 retains frictionally and tele-

2

scopically therewithin, at one end thereof, a holder assembly 11. Said holder assembly 11 comprises a lipstick holder 12 having a walled handle 13 functioning as a receptacle for perfume or any other desired material.

5 The open end of handle 13 is internally threaded at 14 for engagement with the threaded portion of a connector member 15 and to unite assembly 11 and member 15 as a unitary section, the other end of said connector member being exposed outside said outer casing 10 and also 10 being threaded to receive an end cap 16. The removal of said connector member 15 and/or said end cap 16 makes accessible the contents of said handle or receptacle 13. Connector member 15 and/or end cap 16 provide handle means for detaching assembly 11 from outer casing 10. Detachment of holder assembly 11 from outer casing 10 makes accessible the lipstick normally carried within holder 12.

As clearly shown in Figs. 3 and 4, handle member 13 is provided with one or more projections 17 for firm frictional engagement with the inner surface of casing 10. It is apparent that when outer casing 10 and handle member 13 are frictionally engaged and end cap 16 is removed from connection with said handle member 13 to provide access to the contents of said handle member 13, outer casing 10 functions as a handle for handle or receptacle 13. It is apparent that holder assembly 11 serves as a connector for holding end cap 16 axially aligned with outer casing 10 in assembled position.

As clearly shown in Fig. 4, the other end of outer casing 10 frictionally and telescopically retains therewithin a holder assembly or unitary section 18 comprising, in the illustrated embodiment, a tubular cover member 19 and a tubular end member 20. Cover member 19 is provided with an aperture 21 for protrusion of the eyebrow pencil P, shown in Fig. 2, and end member 20 is provided with an aperture 22 for protrusion of lipstick brush 23 or other suitable and desired article. Detachment of holder assembly 18 from outer casing 10 makes accessible the lipstick brush 23.

40 As clearly shown in Fig. 4, cover member 19 is provided intermediate its ends with an annular bead or stop member 24 limiting the extent of insertion of holder assembly 18 within outer casing 10 and the terminal cap member 25. In order to facilitate positive frictional engagement between holder assembly 18 and cap member 25 and outer casing 10, cover member 19 is provided with a plurality of longitudinally extending ribs or ridges 26 spaced about its periphery on opposite sides of annular bead 24. It will be noted that the ribs hold cap member 25 and outer casing 10 in spaced relation to the main body portion of cover member 19.

It is apparent that when outer casing 10 and cover member 19 are frictionally engaged and cap member 25 is removed from its protective position about aperture 21 of cover member 19, outer casing 10 functions as a handle for the protruding end portion 27 of holder assembly 18 while, simultaneously, together with holder assembly 11, connector member 15 and end cap 16 forming an elongated cover cap for lipstick brush 23. It will be noted that holder assembly 18 and cap member 25 may be detached as a unit from outer casing 10, in which case, cap member 25 functions as a handle for the protruding end portion 28 of holder assembly 18 while, simultaneously, protecting end portion 27 of holder assembly 18. In assembled position, cap member 25, holder assembly 18 and outer casing 10 form an elongated cover cap for the open end 29 of lipstick holder 12. It is apparent that holder assembly 18 serves as a connector for holding cap member 25 axially aligned with outer casing 10 in assembled position. As clearly shown in Fig. 2,

65 70 when cap member 25 and end cap 16 are removed from their protective positions, outer casing 10 functions, si-

multaneously, as a handle for receptacle 13 and eyebrow pencil P in use. It will, also, be noted that holder assembly 18 is reversibly frictionally insertable in outer casing 10 and in cap member 25, so that the lipstick brush 23 may protrude from one end of outer casing 10 and cap member 25 may cover lipstick brush 23. Also, it will be noted that upon removal of connector member 15 and end cap 16 from receptacle 13, receptacle 13 may be frictionally inserted first in outer casing 10, so that the open end 29 of lipstick holder 12 will be exposed outside the other end of outer casing 10 opposite to holder assembly 18. It is evident, therefore, that outer casing 10 may serve as a handle for each of the separate elements carried by the device.

As previously pointed out, the device of the present invention is adapted for various combinations of articles for a special purpose in addition to the cosmetic articles illustrated in the preferred embodiment, such as art materials and supplies, drugs, small tools, and the like.

Since certain additional modifications may be made in the device of the present invention without departing from the scope thereof, it is intended that all matter contained in the forgoing specification and shown in the accompanying drawings be interpreted merely as illustrative and not in a limiting sense.

What is claimed is:

1. A kit for housing a plurality of articles related in use comprising a tubular casing open at both ends, a unitary section adapted to present an article at each of its ends and having an end portion thereof detachably, frictionally retained within an end of said tubular casing, the other end portion of said unitary section protruding from said tubular casing, a cap removably, frictionally secured to said other end portion of the unitary section and located entirely outside said tubular casing, a second unitary section having an end portion thereof detachably, frictionally retained within the other end of said tubular casing, said second unitary section being adapted to present an article at said other end of the tubular casing, a second cap located at said other end of said tubular casing and removably secured to said second unitary section and providing handle means for detaching said second unitary section from said tubular casing, said tubular casing and said second unitary section and said second cap forming an elongated cover cap detachable from the first-mentioned unitary section, and said tubular casing providing a handle for articles

at the opposite ends thereof upon removal of said caps from said unitary sections.

2. A kit for housing a plurality of articles related in use comprising a tubular casing, a unitary section adapted to present an article at each of its ends and having an end portion thereof detachably frictionally fitted within an end of said tubular casing, the other end portion of said unitary section protruding from said tubular casing, a removable cap frictionally and telescopically mounted on said other end portion of the unitary section, each end portion of said unitary section being frictionally engageable within both said removable cap and said tubular casing, a second unitary section retained within the other end of said tubular casing and adapted to present an article at said other end of the tubular casing, said tubular casing providing a handle for articles at the opposite ends thereof upon removal of said removable cap.

3. In a kit for housing a plurality of articles related in use, a tubular casing open at both ends and a pair of longitudinally arranged unitary sections, each of said unitary sections being adapted to present an article at each of its ends and each of said unitary sections having an end portion thereof detachably frictionally fitted within opposite ends of said tubular casing, said unitary sections being reversibly frictionally insertable in said tubular casing to permit the use of said tubular casing as a handle for articles at both ends of each of said unitary sections.

4. A kit according to claim 3 including two caps, each of said caps being removably secured to the end portion of one of said unitary sections which is adjacent to opposite open ends of said tubular casing and thereby being maintained in longitudinal relationship to said tubular casing.
